UNITED STATES PATENT OFFICE.

BENJAMIN E. GETCHELL, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

ELECTRIC SWITCH.

Original application filed September 22, 1927, Serial No. 221,215. Divided and this application filed December 27, 1927. Serial No. 242,559.

My invention relates particularly to the general switch construction and the method of mounting and insulating the conducting parts.

5 This is a division from my application #221,215 filed September 22, 1927.

One object of my invention is to provide an extremely compact and efficient double break switch of the remote control type.

10 Another object is to provide a double break switch of the magnetically controlled type in which the circuit is carried through the switch without the necessity of flexible leads.

Another object is to provide a double break

15 switch having movable spring contacts which simultaneously engage the corresponding stationary contacts with an angular or wiping movement.

Another object is to provide a double break 20 switch in which the movable contact members are freely removable for inspection or replacement without the use of tools of any description.

Another object is to provide a double break 25 switch having a movable contact member for simultaneously engaging its corresponding stationary contacts and in which the respective contact ends are flexible with respect to each other and independently self-adjustable 30 with respect to the stationary contacts.

Another object is to provide a remote control switch in which all of the line and load wire connecting means are positioned on one level on the base and all of the remote control 35 wire connecting means are positioned on another level in order to facilitate wiring or to identify the circuits.

Another object is to provide an electric 40 switch having a slotted base and a series of pairs of stationary contacts together with a movable insulating contact-carrying bar positioned between the respective pairs of stationary contacts and having insulating flanges co-operating with the slots in the base to electrically 45 separate the respective pairs of stationary contacts as well as the respective movable contacts.

Another object is to provide an electric 50 switch construction including a molded insulating bar having insulating barriers and

having contact positioning studs and movement guiding plates molded in the material of the bar to form a unit.

Another object is to provide an insulating bar of the preceding description and having 55 an independent circuit connecting strip molded in the material of the bar.

Another object is to provide a unitary carrier for all the movable contacts of a remote-control switch. 60

The accompanying three sheets of drawings illustrate one form of the invention.

Fig. 1 is a front view, the relays being omitted.

Fig. 2 is a side view, a relay such as shown 65 in my former patents being shown separate.

Fig. 3 is a diagrammatic view of the circuits.

Fig. 4 is a side view and vertical section, the switch being shown "closed".

Fig. 5 is a similar view "open". 70

Fig. 6 is an exploded perspective view of one set of main switch contacts.

Fig. 7 is a perspective view of the auxiliary switch contacts.

Fig. 8 is a horizontal section looking up- 75 wardly.

Fig. 9 is a rear view.

The base or body 15 may be formed of insulating material, such as molded composition. In the form shown the side plates 16 80 and 17 are of metal and provided with flanges which are secured to the base by screws, such as 18 and 19. The back plate 20 may be secured to the side plates by screws such as 21. This particular form of back plate is adapted 85 for convenient attachment to a back board or in a switch box (not shown). For convenience this back plate 20 is provided with a keyhole slot 22 at the top by means of which it may be conveniently hung on a screw (not 90 shown). The lower corners of this plate 20 are provided with notches 23 and 24 which open toward one side and toward the bottom for convenience in mounting the plate under the heads of screws (not shown) in an enclosing box. 95

The line terminals 25, 26 and 27 are mounted on the front face of the base along its lower edge. The load terminals 28, 29 and 30 are mounted in the same plane along the upper 100

edge of the base. The terminals 31, 32 and 33 adapted to be connected to a control station or switch are mounted along the upper edge of the base at its rear. The load may be, 5 for instance, a motor (not shown).

The switch has three circuit controlling units in the particular form shown. The left hand unit has stationary contacts 35 and 36 and a movable switch member composed 10 of contact members 37 and 38 connected together by a flexible strip 39 which may be formed of thin laminations so that the two contact members 37 and 38 are free to tilt and rock so as to assure perfect contact with the 15 raised portions 40 and 41 of the stationary contacts.

The back plate 42 has its ends offset from the plane of its central portion 43 and is provided with small bosses 44 adapted to rest 20 against the back of the connecting strip 39 so as to permit relative tilting of the contact pieces 37 and 38. The movable contact parts just described and the corresponding movable contacts for the other switch units are all carried by the insulating member 45 which extends across the base of the switch in the form of a cross bar. This cross bar has set in it a flat stud 46, the end of which extends through slots 47 and 48 and supports a spring 49 30 and a cup-like washer 50. This washer has a central slot 51 to permit it to be slipped on to the end of the stud 46. It also has notches 52 adapted to receive the ends of the T-shaped head of the stud when the washer 50 is rotated through 90 degrees. In this way the movable contact parts may be readily removed and replaced when desired by the simple operation of pressing down upon the washer and turning it with the fingers.

40 The upper contact 35 of the left hand switch unit is electrically and mechanically secured to the terminal 28 by a screw 54. The lower contact 36 is secured to the clip 55 for the relay 56. The lower clip 57 for the relay 45 is electrically and mechanically connected to the lower terminal 25 by screw 58 which may be seated in a suitable insert in the base in any suitable manner. The intermediate clip 59 for the relay is similarly secured to the 50 base.

The right hand switch unit is constructed in the same manner as the one previously described and has stationary contacts 60 and 61 and a movable contact 62. Relay clips 63, 55 64 and 65 for the relay 66 are similarly mounted to those previously described. The central switch unit also has stationary contacts 70 and 71 and a movable contact 72. This unit, however, requires no relay and hence the contact 71 is connected directly to the terminal 26 60 by a strip 73.

The carrier bar 45 is provided with insulating flanges 75 and 76 on opposite sides of the central switch unit to serve as barriers between 65 the switch members of the respective

units. The base 15 is provided with a transverse groove 77 to receive the cross bar 45 which also serves as a barrier between the contacts of each respective pair of the stationary contacts. The base is also grooved at 78 70 and 79 to receive the ends of the flanges 75 and 76, respectively. The opposite ends of the switch carrier 45 are provided with projecting lugs 80 and 81 which are movably mounted in grooves 82 and 83 in the side plates 17 75 and 16 respectively.

A cross connecting contact 85 is mounted in the back of the cross bar 45 and adapted to connect the resilient contact members 86 and 87. The two latter contacts are connected respectively to the control switch terminals 32 and 33 and the operation will be explained hereinafter.

At the back of the base 15 is mounted an electro-magnet and armature. This magnet 85 has a coil 90 one terminal of which is connected to the control switch terminal 31 and the other terminal of the coil is connected to the intermediate clip 59 for the left hand relay 56. The control switch terminal 33 is connected by wire 91 to the intermediate clip 64 for the right hand relay 66. The core of the magnet is preferably laminated in the customary manner and secured to laterally extending cross bars 92 which are slidably supported in the side plates 16 and 17. The magnet core frame is mounted so that it may move vertically in the slots 93 a limited amount. The armature 94 may also be laminated and movable vertically with respect to the magnet coil and core. The armature is connected to the insulating cross bar or contact carrier 45 by a link motion which is supported by the side plates 16 and 17.

Lever plates 95 and 96 of substantially 105 bell crank form are pivoted to the side plates 17 and 16 respectively, and connected to the lugs 80 and 81 of the insulating cross bar by links 97 and 98. Extending from these levers 95 and 96 are connecting rods 99 and 100, the 110 lower ends of which are connected to the ends of the cross bar 101 which carries the armature 94. The connecting rods and links 99 and 100 may be guided between lugs or projections 102 and 103 formed in the side plates 115 16 and 17.

When the magnet is energized it lifts the armature 94 and, through the medium of the connecting links 99 and 100, tilts the lever plates 95 and 96, and thus through the pull 120 of the links 97 and 98 draws the contact carrier 45 toward the base so as to cause the movable contacts to engage the stationary contacts. On account of the inclination of the guide slots 82 and 83 the movable contacts slide upwardly on the stationary contacts until fully seated, thus affording a sliding or wiping contact which insures perfect electrical connection. As the contact carrier 45 is drawn backward and upward toward the 130

base, the springs 49 are compressed, thus insuring an even pressure between the contacts and affording a yielding engagement which prevents shock to the parts of the switch. As 5 the cross piece 85 engages the resilient contacts 86 and 87 additional resiliency is provided to bring the parts to rest without shock. In the form shown the electromagnet is vertically movable being guided in the slots 93 10 which are sufficiently elongated at their upper ends so that even the inertia of the moving armature cannot apply a direct blow on the stationary parts of the mechanism.

The control switch may be of any suitable 15 construction. One form is illustrated diagrammatically in order to facilitate a complete understanding of the method of operation of the invention. In this form the control switch has stationary contacts 105, 106 20 and 107 and movable switch members 108 and 109 which are spring pressed in any suitable manner. Normally the switch member 108 connects the contacts 105 and 106 and the switch member 109 is normally out of contact. 25 The contact 105 is connected to the terminal 31. The contact 106 is connected to the terminal 32 and contact 107 is connected to the terminal 33.

The relay preferably employed in the 30 switch has end caps 110 and 111 adapted respectively to the upper and lower relay clips, and a central external contact 112 connected to the intermediate relay clip. The end caps are connected together by a heating element 35 113 arranged along side of a bi-metallic spring arm 114 whose end normally engages part of the contact 112.

The operation of the switch and the 40 resultant circuits are as follows: Let us consider Fig. 3 as showing the circuit in the "off" position. The opening and closing of the switch is accomplished by the circuits which control the magnet. To close the switch the operator presses the button carried by the contact 109 when the circuit will be as follows: Line terminal 25 to elements 111, 114, 45 112 (of relay 56) coil 90, 31, 105, 108, 106, 109, 107, 33, 91, 112 (of relay 66) 114, 111 to terminal 27.

The above operation has energized the 50 magnet which operates to close the switch and, in this position, a holding circuit is established by the connecting of contacts 86 and 87 by the connector 85, so that the starting button may be released without interrupting the magnet circuit. The circuit is now as follows: Terminal 25 to elements 111, 114, 112, coil 90, 31, 105, 108, 106, 32, 86, 85, 87, 33, 91, 112, 114, 111 to terminal 27. The 55 switch is now automatically held in closed position by the magnet and, normally, can only be opened by interrupting or reducing the strength of the current in the coil current.

Normally the circuit may be opened by 60 pressing the button attached to contact 108,

which, of course, breaks the "running" circuit through the magnet coil and allows the armature to drop and open the switch.

In case of overload the magnet circuit will automatically be opened between 112 and 114 70 of one or both of the relays. In case of failure of line voltage or abnormal drop of line voltage, the magnet will become weakened and unable to hold the armature against gravity and the force of the springs 75 and the armature will drop away from the magnet thus opening the load and magnet switches. After the switch is once opened, it cannot normally be closed again except by 80 manually pressing the button carried by contact 108. This feature is of great value in that it protects the operator against the unexpected starting of the motor or other device after it has once been stopped.

Although I have described the preferred 85 form of the complete apparatus and its method of operation, it should be understood that some of the features herein set forth may be employed independently of others, and are applicable to other types of switches, 90 so also it should be understood that the invention is not limited to the use of the particular thermostatic relay herein set forth. It should also be understood that although I have described the invention as particularly 95 applicable to control from a remote point, certain features may be employed without such limitations, for instance, in some cases the control buttons may be mounted directly 100 upon the box which encloses the main switch. I intend that the claims shall be interpreted broadly as they may appear except as may be required by the state of the art or by the terms thereof.

I claim:

1. In a switch an insulating base, cooperating pairs of spaced stationary contacts carried by said base, said base having a transverse channel extending between the members of each pair of contacts and grooves between the respective pairs of contacts, an insulating cross bar mounted in said channel between the contacts of the respective pairs of contacts, switch members carried by said bar for coacting with the respective pairs of contacts, said bar having insulating flanges between the adjacent switch members and movable in said grooves between the contacts, and means for operating said bar.

2. A switch including an insulating base, switch contacts carried by the front of the base, a carrier at the front of the base, switch members carried by said carrier and adapted to coact with said contacts, a connector carried by said carrier, resilient switch contacts carried by the rear of the base and adapted to be engaged by said connector, and a magnet for operating said carrier.

3. An insulating base having a transverse groove with spaced upper and lower grooves,

rear contacts mounted in the rear of the transverse groove and pairs of other contacts mounted above and below said groove, an insulating cross bar mounted to move in said 5 groove between the upper and lower contacts and having a switch member coacting with said upper and lower contacts and another switch member coacting with said rear contacts, and having an insulating barrier 10 movable in the upper and lower grooves between the adjacent pairs of upper and lower contacts.

4. A switch including an insulating base having a transverse channel, supporting side 15 plates, a movable cross bar guided in said side plates and movable in said channel, stationary contacts supported by said base above and below said channel, a guide stud carried by said cross bar, a switch member 20 resiliently mounted on said stud and having a back plate with centrally disposed bosses contacting with the rear of said switch member and a spring on said stud pressing against said back plate.

25 5. A switch including an insulating base, switch contacts mounted on the front of said base, circuit terminals for said contacts at the upper and lower ends of said base and in a common plane, a switch member movable 30 toward and from said contacts, an auxiliary connector movable with said switch member, contacts mounted at the rear of said base for coacting with said auxiliary connector, and

circuit terminals mounted at the rear of said base and accessible from the front of said 35 base and electrically connected with the rear contacts.

6. A switch including metal side plates having guide slots, an insulating base mounted between said side plates and having a 40 transverse channel, contacts mounted on said base at opposite sides of said channel, a cross bar movable in said channel and guided in said slots, a switch member carried by said cross bar and coacting with said contacts, 45 said base having additional channels at opposite sides of said first mentioned channel, and said cross bar having insulating flanges movable in said channels on opposite sides of said switch member and between said switch 50 member and the side plates.

7. A switch including metal side plates having guide slots, an insulating base mounted between said side plates and having a 55 transverse groove, contacts mounted on said base above and below said groove, a cross bar movable in said groove and guided in said slots, a switch member carried by said cross bar and coacting with said contacts, said base having grooves above and below said 60 channel and said cross bar having insulating flanges movable in said grooves on opposite sides of said switch member and between said switch member and the side plates.

BENJAMIN E. GETCHELL.
